UNITED STATES PATENT OFFICE.

GUY MARION HATFIELD, OF PAWNEE, OKLAHOMA TERRITORY.

DESIGN FOR A CLOTHES-PIN.

SPECIFICATION forming part of Design No. 31,184, dated July 11, 1899.

Application filed May 20, 1899. Serial No. 717,652. Term of patent 14 years.

To all whom it may concern:

Be it known that I, GUY MARION HATFIELD, a citizen of the United States, residing at Pawnee, in the county of Pawnee and Territory of Oklahoma, have invented and produced a new and original Design for Clothes-Pins; and I do hereby declare the following to be a full, clear, and exact description of the same, reference being had to the accompanying drawings, forming a part thereof.

The invention relates to an original design for a clothes-pin; and it is embodied in the peculiar formation and arrangement herein-after described, and shown in the drawings.

In the drawings the design is shown in Figure 1 in front elevation, and Fig. 2 is an end elevation.

The characteristic feature of the design resides, primarily, in two scroll-shaped side pieces A, with a center spiral or body portion B, connecting the same and from the ends of which the scrolls spring or extend. The scroll side pieces are bent downward, and their end portions are turned up and then bent laterally, substantially U-shaped. (Shown in Fig. 2 at

C.) The extreme end portions are carried vertically upward and formed with suitable eyes D. In the arrangement shown the scrolls are on opposite sides, and the upturned end portions with the eyes D are consequently arranged diagonally opposite. The concaved faces of the U-shaped pieces are arranged to coincide or register with the central bore of the body-piece B.

The essential features of the design consist in the curved or scroll-shaped side pieces with the upturned end pieces and body portions, substantially as shown.

Having thus described the design, what I claim as new, and desire to secure by Letters Patent, is—

The design for a clothes-pin, substantially as shown and described.

In testimony whereof I affix my signature in the presence of two witnesses.

GUY MARION HATFIELD.
